UNITED STATES PATENT OFFICE.

HOWARD J. KERR, OF ELIZABETH, NEW JERSEY, ASSIGNOR TO THE BABCOCK & WILCOX COMPANY, OF BAYONNE, NEW JERSEY, A CORPORATION OF NEW JERSEY.

PROTECTION FOR WATER-TUBE-CLEANING ELEMENTS.

Application filed October 4, 1923. Serial No. 666,467.

To all whom it may concern:

Be it known that I, HOWARD J. KERR, a citizen of the United States, residing at Elizabeth, in the county of Union and State of New Jersey, have invented certain new and useful Improvements in Protection for Water-Tube-Cleaning Elements, of which the following is a specification.

My present invention relates to improvements for protecting water tube cleaning elements, particularly where such elements are exposed to extremely high heat and will be best understood from the following description and the annexed drawing in which Fig. 1 is a side elevation, of a well-known form of water tube boiler with some of the parts broken away and embodying an illustrative form of my invention; Fig. 2 is an enlarged section on the line 2-2 of Fig. 1; Fig. 3 is a section on the line 3-3 of Fig. 2 and Fig. 4 is a perspective of a detail.

Like parts are indicated by like reference characters.

In the illustrative embodiment, the boiler has vertical uptake headers 10 and downtake headers 11, connected by water tubes 12, the two lower rows 13 and 14 being spaced from the main bank of the water tubes and a row of tubes 15 connecting the mud drums 16 and 17. Transverse vertical baffles 18 and 19 extend across the main bank of tubes and a longitudinal baffle 20 extends above the tubes 13 to a vertical baffle 21 which, in turn, connects with a longitudinal baffle 22 extending to the transverse baffle 18.

The lowermost rows of tubes 13, 14 and 15 are exposed for substantially their entire length of the furnace gases which sweep across them and into the first pass formed between the headers 10 and the transverse baffle 18.

In order to remove deposits, such as slag, from the lowermost rows of tubes 14 and 15, I have found it desirable to provide a blower tube between the ends of these tubes to direct jets of steam or other fluid along the surfaces of the water tubes. This brings such blower tubes directly in the path of the gases sweeping up from the furnace and also exposes them to the direct radiant heat from the furnace. Under these extreme heating conditions, the blower tubes are liable to be burned out unless they are thoroughly protected and such protection is pro-

vided in the arrangement illustrated by 55 forming a substantially continuous cover for the blower tube and providing channels or ducts in such continuous cover through which the jets of steam or other fluid used to clean the tubes may be directed. 60

In the illustrative embodiment, the blower tube 23 extends across the water tubes in the usual manner and is encased by a metallic cover made up of metallic covering members or blocks 24 placed end to end. 65

Each block is made up of two parts by dividing the block in a plane parallel with the axis of the tube 23, each part having a recess 25 adapted to fit the water tube to which it is connected. Each part of each 70 block has a projection 26 provided with a semi-cylindrical recess 26' which, when mated with a corresponding semi-cylindrical recess 26' in the other part of the block, forms a tubular opening surrounding the 75 blower tube 23.

Each part of each block 24 is provided with a loop 27, surrounding the water tube and having its ends extending through the member 24, nuts 28 serving to draw the surface of the recess 25 against the water tube to provide a close thermal contact between the block and the water tube. By reason of this close thermal contact the members 24 with their protecting hoods 26 are maintained at the relatively cool temperature 80 of the water tubes themselves. 85

In the illustrative arrangement, recesses 29 are formed in the ends of each of the members 24 so that when these members are 90 placed end to end, an opening or duct is formed from the cylindrical opening 26' for the blower tube 23 to the exterior of the member. In the illustrative arrangement, nipples 30 extend from the blower tube 23 through the openings 29 to direct the cleaning jets along the water tubes, the steam or other cleaning fluid being supplied to the ends of the blower tubes 23 through suitable piping, as shown in dotted lines in Figure 1 100 in a well-known manner.

Preferably the members 24 are arranged so that they will form a continuous barrier across the water tubes beneath the blower tubes 23. In the illustrative arrangement, 105 a tight joint for this purpose between the end of the members 24 is provided by forming a lip 31 at one end of each member 24

and a corresponding recess 32 at the opposite end. Preferably also the inner edge of one of each set of members 24 is provided with a recess 33 into which extends a projection 34 on the member 24 of the pair. By the means illustrated, a substantially gas-tight joint, regardless of relative motion between the water tubes, is formed between the blocks 24 so that no radiant heat can reach the blower tube 23 and so that the gases are diverted from the blower tube. By this means, together with the entire covering of the tube 23 and the close thermal contact between the members 24 and the water tubes, the blower tube 23 will be kept sufficiently cool to prevent its destruction.

While in the arrangement illustrated, I have provided nipples 30 extending through recesses in the members 24, it will be understood that, if desired, the recess 29 may be used to direct the steam jets from the boiler tube 23, thus eliminating the nipples 30.

In the illustrative arrangement I have shown two blower tubes each arranged as described, one of the tubes being arranged to clean the water tubes 15 and the other the water tubes 14. As a further protection, I preferably place these tubes and their casting close together and fill the spaces between them with some refractory material such as asbestos, as shown at 34 in Figure 1.

By dividing the blocks 24 into two parts each, the parts may be readily disassembled and assembled. The recesses 29 are formed of such size and shape that when a loop 27 is loosened and removed, its part of the block may be moved along the water tube to free it from the other part and the nipples 30 and, of course, an opposite course may be followed in assembling the parts.

It will be understood that the arrangement shown in the drawing is merely illustrative and that the embodiment of my invention may be widely varied.

I claim:

1. In a water tube boiler, a blower element extending across a row of water tubes in the path of gases flowing across the tubes, and a metallic cover and support for said element comprising a plurality of metal blocks, each having a tubular opening surrounding the blower element and said blocks being arranged end to end to form a continuous tubular opening extending the length of the element and each block having an extended surface adapted to fit against a water tube, and means on each block to connect it to one water tube only and to draw its extended surface into contact with the water tube, said blower element having lateral jet elements extending

from the sides thereof through ducts formed in said blocks.

2. In a water tube boiler, a blower element extending across a row of water tubes in the path of gases flowing across the tubes and a metallic cover and support for said element comprising a plurality of metal blocks, each having a tubular opening surrounding the blower element and said blocks being arranged end to end to form a continuous tubular opening extending the length of the element and each block having an extended surface adapted to fit against a water tube, and means on each block to connect it to one water tube only and to draw its extended surface into contact with the water tube, said blower element having lateral jet elements extending from the sides thereof through ducts formed in said blocks, a part of each duct forming a recess in the end of each of said blocks.

3. In a water tube boiler, a blower element extending across a row of water tubes in the path of gases flowing across the tubes, and a metallic cover and support for said element comprising a plurality of metal blocks, each having a tubular opening surrounding the blower element and said blocks being arranged end to end to form a continuous tubular opening extending the length of the element and each block having an extended surface adapted to fit against a water tube, and means on each block to connect it to one water tube only and to draw its extended surface into contact with the water tube, said blower element having lateral jet elements extending from the sides thereof through ducts formed in said blocks, a part of each duct forming a recess in the end of each of said blocks and each pair of adjacent blocks being provided with overlapping adjacent portions to form a barrier for the gases beneath the water tubes.

4. In a water tube boiler, a blower element extending across a row of water tubes in the path of gases flowing across the tubes, and a metallic cover and support for said element comprising a plurality of metal blocks, each block being formed of two parts divided in a plane parallel to the axis of the blower tube, fastening means for each part to attach it to the water tube, each of said blocks having a tubular opening extending therethrough with a part of such opening in each part of the block, and the blocks being arranged end to end to form a continuous tubular opening extending the length of the blower element, said blocks having lateral ducts therein extending from the exterior to said tubular opening.

HOWARD J. KERR.
